United States Patent Office

Des. 227,322
Patented June 19, 1973

227,322

CHAIR

Don Ray Gill, Hammond, Ind., assignor to Mohasco
Industries, Inc., Amsterdam, N.Y.

Filed Apr. 22, 1971, Ser. No. 136,637

Term of patent 14 years

Int. Cl. D6—02

U.S. Cl. D6—68

FIG. 1

FIG. 2

FIG. 1 is a front perspective view of a chair showing my design; and

FIG. 2 is a side perspective view thereof.

The back of the chair is conventionally plain while the side not shown is substantially identical to the side shown.

I claim:

The ornamental design for a chair, as shown and described.
